DESIGN FOR A REFRIGERATOR CABINET OR SIMILAR ARTICLE

Ralph E. Kruck, Springfield, Mass., assignor to
Westinghouse Electric & Manufacturing Com-
pany, a corporation of Pennsylvania

Application April 4, 1940, Serial No. 91,478

Term of patent 7 years

To all whom it may concern:

Be it known that I, Ralph E. Kruck, a citizen
of the United States, residing at Springfield, in
the county of Hampden and State of Massa-
chusetts, have invented a new, original, and or-
namental Design for a Refrigerator Cabinet or
Similar Article, of which the following is a speci-
fication, reference being had to the accompany-
ing drawing, forming a part thereof.

The figure is a front perspective view of a re-
frigerator cabinet or similar article, showing my

new design. The side of the cabinet not shown
is identical with the side illustrated and the rear
is flat and plain.

The dominant feature of the design resides in
the body of the refrigerator cabinet or similar
article, as shown by full lines.

I claim:

The ornamental design for a refrigerator cab-
inet or similar article, substantially as shown and
described.

RALPH E. KRUCK.
